UNITED STATES PATENT OFFICE.

HARRY BASHINSKI, OF MACON, GEORGIA.

DESIGN FOR A WATCH-CHARM OR SIMILAR ARTICLE.

40,750.

Specification for Design.

Patented July 5, 1910.

Application filed April 19, 1910. Serial No. 556,453. Term of patent 7 years.

To all whom it may concern:

Be it known that I, HARRY BASHINSKI, a citizen of the United States, residing at Macon, in the county of Bibb and State of Georgia, have invented a new, original, and ornamental Design for Watch-Charms or Similar Articles, of which the following is a specification, reference being had to the accompanying drawing, forming a part thereof.

This invention relates to an improved design for watch charms or similar articles.

In the drawings the figure is an elevation of an artillery carriage wheel designated by

the numeral 5 having in the hub thereof one trunnion of a cannon 6, the opposite trunnion bearing a portion of a carriage 7. Embracing the butt end of the cannon is a portion of the national ensign 8, while poised on the cannon and at the middle thereof is a spread eagle 9.

I claim:—

The ornamental design for a watch charm or similar article, as shown.

HARRY BASHINSKI.
